(Cl. D58—12)

To all whom it may concern:

Be it known that I, Clemens Kraml, a citizen of the United States of America, residing in Iberia, Miller County, Missouri, have invented a new, original, and ornamental Design for Novelty Boxes, of which the following is a specification, reference being had to the accompanying drawing, forming part thereof.

In the drawing—

Fig. 1 is a top plan view of a novelty box, showing my new design.

Fig. 2 is a front view thereof.

Fig. 3 is an end view thereof.

I claim:

The ornamental design for a novelty box, as shown.

CLEMENS KRAML.
